GARDEN HOE

Ethan Grant, P.O. Box 2083, Salem, Oreg.

Filed May 9, 1963, Ser. No. 74,827

Term of patent 14 years

(Cl. D39—1)

FIG. 1 is a side elevation of a garden hoe showing my new design.

FIG. 2 is a fragmentary top plan view thereof; and FIG. 3 is a bottom plan view thereof.

The center of the handle disclosed in FIG. 1 is broken away to indicate indeterminate length. The complete handle is omitted in FIGS. 2 and 3 and the connector member is fragmentarily shown in FIG. 2 for convenience of illustration.

I claim:

The ornamental design for a garden hoe, as shown and described.
